(57) **CLAIM**

The ornamental design for a fluid connector, as shown and described.

DESCRIPTION

FIG. 1 is a front left perspective view of a fluid connector showing our new design;

FIG. 2 is a rear view of the design shown in FIG. 1;

FIG. 3 is a front view of the design shown in FIG. 1;

FIG. 4 is a right side view of the design shown in FIG. 1;

FIG. 5 is a left side view of the design shown in FIG. 1;

FIG. 6 is a bottom view of the design shown in FIG. 1; and,

FIG. 7 is a top view of the design shown in Figure.

The broken lines shown in the figures are included for the purpose of illustrating portions of the fluid connector that form no part of the claimed design.

1 Claim, 7 Drawing Sheets(56)
